UNITED STATES PATENT OFFICE.

CALDER S. SHERWOOD, OF PORTSMOUTH, VIRGINIA.

DESIGN FOR A SPOON.

SPECIFICATION forming part of Design No. 20,858, dated June 23, 1891.

Application filed May 16, 1891. Serial No. 393,034. Term of patent 3½ years.

To all whom it may concern:

Be it known that I, CALDER S. SHERWOOD, a citizen of the United States, residing at Portsmouth, in the county of Norfolk and State of Virginia, have invented and produced a new and original Design for Spoons, of which the following is a specification, reference being had to the accompanying drawing, forming a part thereof.

10 The design is intended to be applied to or worked upon the face of both handle and bowl of a spoon not differing greatly from the ordinary form. The broader portions of the handle are ornamented near the edge by a 15 line and simple scroll and shell-like figures, and at the end of the handle is a medallion or circular shield bearing a coat of arms. The shield is somewhat less in diameter than the width of the adjacent portion of the handle, 20 which is rounded inward upon each side in a crenate line to meet the shield at diametrically-opposite points. The whole length of the spoon from the shield to the tip of the bowl is occupied by the main portion of the 25 design, which is a representation of Fortress Monroe and the adjacent coast looking landward. The center line of the picture is approximately coincident with the medial line of the spoon, so that the upper half of the 30 spoon is occupied by the land and the sky

above it and the lower half or foreground by the water of the picture. The fort appears at the right, near the shield, with a light-house still farther to the right and a little to the left large buildings of a non-military character. Still farther to the left, near the bowl 35 of the spoon, are other buildings of the same general kind as those last named, and beyond these the land extends to the left nearly to the tip of the bowl. In the foreground, on 40 the wider part of the bowl, appear two vessels of the *Monitor* and *Merrimac* types, respectively, and in the foreground near the fort are small sail and steam vessels.

The whole design is worked upon the metal 45 in intaglio or relief, or a combination of the two, and its characteristic features are a land-and-water view or picture extending from the tip of the bowl to a medallion at the end of the handle, which latter bears marginal 50 ar- besque and shell-like ornamentation.

What I claim is—

The design for a spoon herein shown and described.

In testimony whereof I affix my signature in 55 presence of two witnesses.

CALDER S. SHERWOOD.
